CHARLES S. BUSHNELL, OF ROCHESTER, NEW YORK, ASSIGNOR TO GENERAL RAILWAY SIGNAL COMPANY, OF ROCHESTER, NEW YORK, A CORPORATION OF NEW YORK.

ELECTRICALLY-OPERATED SEMAPHORE-SIGNAL.

1,377,392.

Specification of Letters Patent. Patented May 10, 1921.

Application filed September 1, 1920. Serial No. 407,301.

To all whom it may concern:

Be it known that I, CHARLES S. BUSHNELL, citizen of the United States, residing at Rochester, in the county of Monroe and 5 State of New York, have invented certain new and useful Improvements in Electrically-Operated Semaphore-Signals, of which the following is a specification.

This invention relates to electrically operated 10 semaphore signals used in railway signal systems.

Semaphore signal operating mechanisms in common use, while differing to a certain extent in details of construction, generally 15 include some form of a holding or retaining mechanism, herein conveniently termed a hold-clear device, for holding the semaphore blade in its one or more operated positions, corresponding to caution or proceed. Since this hold-clear device is energized 20 the greater part of the time, its efficiency is an important part of the total efficiency or economy of the system. The hold-clear devices commonly used, and with 25 which I am familiar, are of the type comprising a latch or detent operated by an electromagnet. It is a well known characteristic of this type of hold-clear device that the energy required to place the device in 30 its operated position, or pick it up, is somewhat greater than that required to retain the device in its operated condition, or hold it up. This characteristic is due to the well 35 known fact that the current in an electromagnet required to attract its armature, is greater than the current needed to hold the armature in its attracted position. In order to make the current through the hold-clear device at different times correspond more 40 nearly to that required, it has been proposed to provide a hold-clear magnet with a low resistance winding and a high resistance winding, and use the low resistance winding for picking up the device, and the two 45 windings in series for holding the device in its operated position. This change in circuit connections is made by automatic devices, which are preferably so constructed that the change is not made until the armature 50 of the hold-clear magnet has fully attained its attracted position, and also without interrupting the current through the windings of said magnet. In addition to these requisites, there sometimes occurs in 55 practice temporary interruptions in the supply of current to the hold-clear device, due

for example, to the vibration of contacts of relays or switch boxes by passing trains. Such interruptions of current may cause the hold-clear magnet to drop its armature, and 60 since it cannot pick up until its pickup circuit is established, it is desirable to make a change from the holding circuit back to the pickup circuit quickly, and particularly before the semaphore has had opportunity to 65 drop back to any great extent, otherwise there is false and objectionable movement of the semaphore to its caution or stop position.

In certain applications of semaphore signal operating mechanisms, it is desirable to use the hold-clear device to perform the functions of a relay. For example, the circuit for controlling one operated position of the semaphore, usually the caution position, 70 may be of considerable length and include a number of switch box or lever contacts, so that this circuit cannot be used to advantage for an operating circuit of the motor, but must be relayed. It is the primary purpose of the present invention to meet the foregoing conditions and requisites; and one of the principal objects of my invention is to devise an organization and arrangement 75 of parts and circuits capable of satisfying these requirements in a simple and efficient manner, together with other conditions found in the practical operation of railway signal systems. Other specific objects and advantages of the invention will appear 80 hereinafter as the description progresses.

In describing the invention in detail, reference will be made to the accompanying drawings, in which

Figure 1 is a diagrammatic view of a 95 semaphore signal operating mechanism embodying my invention, the parts of said mechanism being spread apart and shown more with a view of making it easy to understand the construction and operation, 100 than with the idea of showing the construction and arrangement preferably employed in practice; and

Fig. 2 is a wiring diagram showing one 105 application of my improved semaphore signal operating mechanism.

Referring to Fig. 1, I have illustrated my invention applied to a semaphore signal operating mechanism of well known construction, comprising a semaphore shaft 1, to 110 which the semaphore blade C is fastened, this blade being arranged in the usual way

so that it tends to move by its own weight from the vertical position shown (conveniently termed the 90° position) to a horizontal position against a suitable stop 5 (shown diagrammatically at 2), this horizontal position being conveniently termed the 0° position. The shaft 1 is connected by reduction gearing 3 to a motor shaft 4. The operating motor M is shown in a simplified manner, and comprises the usual field 10 and an armature 6 secured to the shaft 4.

The hold-clear device comprises a toothed wheel 7, which is preferably connected to the shaft 4 by a combined friction and ball 15 clutch device, so that said toothed wheel may turn freely with respect to the shaft 4 in one direction, but is held against turning, except for the slipping of the friction clutch, in the other direction, these directions of movement corresponding respectively with the movement of the semaphore toward its 90° or operated position, and toward its horizontal or 0° position. Coöperating with the toothed wheel 7 is a detent 20 or latch mechanism, comprising two plates 8 pivotally supported at their upper ends on a suitably fixed member 9 (which in practice forms a part of the mechanism case). A pawl 10 is guided between said plates by 25 pins 11 and is spring pressed inward toward the toothed wheel 7 by a spring 12. The plates 8 have a pin and slot connection at their lower ends to the short arm of an angle lever 13, pivotally supported on fixed 30 members 14. To the long arm of the lever 13 is connected the armature 15 of the hold-clear magnet 16. This magnet is fastened to a member 17 forming part of the mechanism casing, and is provided with low resistance coils or windings L and high resistance coils or windings H. A stop pin 35 18 secured to the lever 13 is arranged to engage a suitably fixed member 19, so as to limit the downward movement of said angle lever. Attached to the long arm of the angle lever 13 and insulated therefrom is a bracket 20 which has a pin and slot connection to the switch member 21. This switch member has the general shape of a cross, 40 and is pivotally supported at its upper end to a block 22 of insulating material suitably fastened to a portion of the mechanism case. Contacts 23 and 24, shown conventionally as arrows, are suitably supported 45 to coöperate with the arms of the switch member 21. The operation of the hold-clear mechanism is as follows. The parts are shown in a picked up or operated position, pawl 10 being in engagement with one of 50 the teeth of the toothed wheel so as to prevent rotation of the motor shaft 4 (in the counterclockwise direction) and thereby hold the semaphore blade C in its vertical position. At this time the high and low 55 resistance coils of the hold-clear magnet

16 are connected in series, in a manner more fully explained hereinafter. When the hold-clear magnet 16 is deënergized, the angle lever 13 and armature 15 drop, due to their own weight, and this withdraws the 70 pawl 10 from engagement with toothed wheel 7, thereby permitting the semaphore blade to move toward its biased position. At the same time the switch member 21 is shifted out of engagement with contact 24 75 into engagement with contact 23, for the purposes hereinafter explained. When the hold-clear magnet 16 is again energized, its armature 15 is attracted, and the pawl 10 is projected into engagement with teeth on 80 the wheel 7. The ball clutch connection between this wheel 7 and the shaft 4, however, permits the shaft 4 to turn freely while the wheel is held stationary.

The circuit controller of the signal operating mechanism comprises a drum 25 of wood or other suitable insulating material fastened by screws to a shaft 26, which is connected by segmental gears 27, 28 to the semaphore shaft 1. Associated with the 90 drum 25 are a number of contact groups, each of these groups consisting of a pair of contact springs 29, and a contact strip, or strips 30 on the drum 25. The contact springs 29 are carried by bars 31 of suitable 95 insulating material, which in turn are fastened to the framework of the circuit controller. By making the contact strips on the drum of the appropriate length and position, the various pairs of contact springs 100 29 may be connected electrically in any desired position of the drum 25 and throughout any desired range of its movement.

Also associated with the drum 25 is a device, conveniently termed a slip contact S. In 105 the particular construction illustrated, this slip contact comprises a shoe-like slip member 32 riding in a shallow groove around the drum 25. This slip member 32 is pressed against the drum 25 by a spring 33, the connection between said member and said spring being preferably made by a pin fitting loosely in sockets therein, so that the member 32 may travel with the drum 25 to a limited extent in either direction. A 110 contact spring 34 is arranged to be engaged by the slip member 32, when said member is carried in one direction. The friction between the slip member 32 and the drum 25 is sufficient to cause movement of said slip 115 member into and out of engagement with the contact spring 34. The circuit connections controlled by the slip contact S are between the springs 33-34.

In order to explain the various features 120 of the construction and operation of my improved semaphore signal operating mechanism, I have illustrated in Fig. 2 one practical application of this mechanism. Referring to Fig. 2, there is illustrated in a con- 125 130

ventional manner two track sections or blocks A and B, with track relays 35, signals 36 and 37 at the entrance to said blocks, and the parts and circuits associated with 5 the signal 36. The contact groups of the circuit controller are shown according to established convention at 38 and 39, as switch arms moving with the semaphore blade 36 and making contact with curved 10 segments through the angles of movement of said blade indicated. For example, circuit controller 38 makes contact from 0 to 47°. D designates a line relay of the usual construction controlled by a circuit controller 40 operated by the signal 37, said circuit controller being closed so as to energize the relay D, when the semaphore 37 is in the 15 45° or caution position, or the 90° or proceed position, or any position in between. 20 K designates a switch box contact, or the contact of a lever, or the like. The other parts shown in Fig. 2 correspond to those illustrated in Fig. 1 already described, the same reference characters being employed. 25 Operation: The parts and circuits are shown in Figs. 1 and 2 corresponding to the proceed position of the semaphore. At this time the hold-clear magnet 16 is energized with its coils H and L in series, by a circuit 30 which may be traced as follows: commencing at battery 41, wire 42, contact K, wire 43, front contact 44 of track relay 35, wires 45 and 46, front contact 47 of relay D, wires 48 and 49, coils L, wires 50 and 51, coils H 35 and wires 52 and 53 back to the battery. The other circuits are open. When a train enters the block A and drops track relay 35, it opens the holding circuit of the hold-clear magnet 16, and allows its 40 armature 15 to drop. This releases the semaphore blade and allows it to gravitate toward its stop position. At the same time the switch member 21 is shifted, thereby establishing a snubbing circuit through the 45 motor M, said circuit comprising wire 54, switch member 21, contact 23, wire 55, snubbing resistance 56, wire 57, and through the armature 6 and field 5 of motor M. The motor M having a low resistance shunt 50 around its armature and field acts as a generator, thereby retarding the movement of the semaphore blade and associated gearing, so that it stops in the horizontal position without severe shock and jar. During the 55 movement of the semaphore blade toward its biased position the circuit controller drum 25 is turned in the direction (counter-clockwise as shown in Fig. 1) to move the slip member 32 into engagement with spring 60 34, so as to establish an electrical connection between springs 33 and 34. This closes a low resistance shunt for the coils H of the hold-clear magnet 16 comprising wires 51, 58, slip contact and wires 59 and 52. 65 When the train leaves the block A and passes entirely into the block B, the track relay 35 again picks up. Signal 37, however, assumes the stop position and opens its circuit controller 40, so that relay D is deenergized. Under these conditions a circuit is established through the low resistance coils L of the hold-clear magnet 16, high resistance coils H being shunted by the slip contact S, this circuit being through the circuit controller 38 of the signal 36 now closed 70 because signal 36 is in the 0° position. The current from battery 41 through the low resistance coils L is sufficient to attract the armature 15 of the hold-clear device, thereby shifting the switch member 21 back to 75 the position shown and establishing an operating circuit for the motor as follows: commencing at battery 60, wire 61, circuit controller 39, (now closed), wire 62, contact 24, switch member 21, wire 54, field 5 and 80 armature 6 of the operating motor M and wire 63 back to the battery. The motor drives the semaphore from its horizontal or 0° position toward its vertical position. When the armature 15 picks up, the pawl 90 10 is projected into engagement with the toothed wheel 7; but on account of the ball clutch connection between the wheel 7 and the shaft 4, said shaft may rotate freely while the wheel 7 is held stationary. After 95 a few degrees movement of the semaphore shaft 1, from 2 to 5 degrees, the circuit controller drum 25 carries with it the slip member 32 out of engagement with the spring 34, thereby interrupting the shunt around 100 the high resistance coils H, and placing these coils in series with the coils L. The armature 15 being attracted at this time, the smaller current flowing through the coils H and L in series is sufficient to hold up 105 this armature. When the semaphore blade attains about 43°, that is, about 2° below its 45° or caution position, the circuit controller 39 opens and interrupts the operating circuit for the motor M. The semaphore 110 blade and associated gearing, however, usually move a little farther by virtue of the acquired momentum, so that finally it is brought to rest at its 45° or caution position and is held there by the pawl 10 co-operating with the wheel 7, the hold-clear magnet 16 being maintained energized through the circuit controller 38 which is closed from about 0° to 47°. 115 When the train assumed to be in the block 120 B, leaves this block, the signal 37 is operated to the caution position, closes its circuit controller 40, and energizes relay D. Current is now supplied to the operating motor M from battery 60 along wires 61 125 and 64, front contact 65 of relay D, wire 66, circuit controller 39 (closed from about 40° to 88°), wire 62, contact 24, switch member 21, wire 54, field 5 and armature 6 of motor M and wire 63 back to the battery. 130

Current is maintained on the hold-clear magnet 16 through wires 46 and 48 and front contact 47 of relay D; and the signal is operated to its 90° or vertical position 5 and held there.

In addition to the movements already described, occasionally the semaphore is moved from the 90° position to the 45° position, as for example when a train backs into the 10 block B from the block ahead. During this movement of the semaphore, the hold-clear magnet 16 drops as before, and closes the snubbing circuit for the motor. Also the slip contact S closes; and at about 47° the 15 hold-clear magnet 16 picks up again through circuit controller 38. The semaphore blade and its associated gearing, however, acquires considerable momentum during its downward movement and cannot be 20 instantly brought to a stop. Consequently, when the pawl 10 is thrown into engagement with the toothed wheel 7 at about 47°, the friction clutch between said wheel and the shaft 4 slips and the blade drops still 25 farther a few degrees below the 45° position. When the semaphore drops below 43° the motor operating circuit is established at circuit controller 39, thereby starting to drive the semaphore upward again. During 30 this upward movement the slip contact S opens and throws the coils H and L in series. At about 43° the motor operating circuit is broken, and after a little more upward movement, the semaphore settles back and is 35 held in its 45° position by the hold-clear device.

It sometimes happens in practice that a circuit controlling signal is momentarily interrupted. For example, a switch box 40 contact, as K, may be poorly adjusted and perhaps the contact surfaces are dirty, so that the jar and vibration of a passing train opens the circuit temporarily. This, of course, deenergizes the hold-clear magnet 45 16; but in accordance with the present invention, this magnet may pick up again as soon as the semaphore blade moves back a few degrees, since the slip contact is closed by such movement and puts the low resistance coil L alone in the circuit.

It will be observed that the change from the low resistance pickup circuit to the high resistance holding circuit of the hold-clear device is made by the movement of the 50 semaphore circuit controller, and since this movement cannot occur until after the switch member 21 has shifted, it is assured that the armature of the hold-clear device is fully attracted before this change is made. 55 In other words, a change from the pickup to the holdup circuit is made by parts set into operation by the attraction of the armature of the hold-clear device but sufficiently slow acting to assure that said armature has

attained its fully attracted position, regardless of any delicate or precise adjustment of contacts. Another important feature of the invention is the ability of the semaphore operating mechanism to pick up at any part 60 of its movement, so that temporary interruptions of current do not send the semaphore all of the way back to its 0° position before it can return to its operated position.

The particular construction and arrangement of parts and circuits illustrated may 65 be modified and adapted to suit varying requirements without departing from the invention.

What I claim as new and desire to secure by Letters Patent of the United States is:— 70

1. In a semaphore signal operating mechanism, the combination with a hold-clear device having a pickup circuit and a holding circuit, of means operated in accordance 75 with the direction of movement of the semaphore for controlling said circuits.

2. In a semaphore signal operating mechanism, the combination with a hold-clear device having a pickup circuit and a holding circuit, of means responsive to the direction of movement of the semaphore for causing alternate closing of said circuits as the semaphore moves a few degrees in opposite directions. 90

3. In a semaphore signal operating mechanism, the combination with a hold-clear device having a pickup circuit and a holding circuit, of slow-acting means responding to the energization of said device for changing from the pickup circuit to the holding circuit without interrupting the flow of current. 95

4. In a semaphore signal operating mechanism, the combination with a hold-clear device having a high resistance coil and a low resistance coil, a pickup circuit including the low resistance coil alone, a holding circuit including said coils in series, and means operated in accordance with the direction of movement of the semaphore for establishing said circuits in succession without interrupting the flow of current. 105

5. In a semaphore signal operating mechanism, the combination with a hold-clear device having a pickup circuit and a holding circuit, of means for changing from the pickup circuit to the holding circuit as the semaphore moves a few degrees toward its operated position and for changing from the holding circuit to the pickup circuit as the semaphore moves backward a few degrees from its existing position toward its biased position. 115

6. In a semaphore signal operating mechanism, the combination with a hold-clear device having a low resistance coil and a high resistance coil, a shunt for the high resistance coil, and means for opening and 120

closing said shunt as the semaphore moves a few degrees toward its operated position and biased position respectively.

7. In a semaphore signal operating mechanism having a hold-clear device and an operating motor, an operating circuit for the motor, circuit controlling means actuated by the hold-clear device for controlling the operating circuit, a pickup circuit and a holding circuit for the hold-clear device, and means responsive to the direction of movement of the semaphore for controlling the circuits of said device.

8. In a semaphore signal operating mechanism having a hold-clear device and an operating motor, an operating circuit for the motor, circuit controlling means actuated by the hold-clear device for controlling the operating circuit, a pickup circuit and a holding circuit for the hold-clear device,

and a slip contact responding to the direction of movement of the semaphore for alternately establishing the circuits of said device, said slip contact being shifted after a few degrees movement of the semaphore. 25

9. In a semaphore signal operating mechanism having an operating motor and a hold-clear device provided with high resistance and low resistance coils, an operating circuit for the motor, means actuated by the hold-clear device for controlling the operating circuit, a shunt for the high resistance coil, and a slip contact for opening and closing said shunt, said slip contact being shifted by a few degrees movement of the 30 semaphore in opposite directions. 35

In testimony whereof I have affixed my signature.

CHARLES S. BUSHNELL.
